(57) **CLAIM**

We claim the ornamental design for a sink, as shown and described.

DESCRIPTION

FIG. 1 is a perspective view of the claimed design; FIG. 2 is a front view of the claimed design shown in FIG. 1; FIG. 3 is a rear view of the claimed design shown in FIG. 1; FIG. 4 is a top view of the claimed design shown in FIG. 1; FIG. 5 is a bottom view of the claimed design shown in FIG. 1; FIG. 6 is a side view of the claimed design shown in FIG. 1; and, FIG. 7 is another side view of the claimed design shown in FIG. 1.

The broken lines formed by equal length dashes show portions of the sink that form no part of the claimed design. The broken lines formed of unequal length dashes (i.e., dash-dot) show boundaries of the claimed design and form no part thereof.
